CLAIM

The ornamental design for an identification tag for a bag, as shown and described.

DESCRIPTION

FIG. 1 is a perspective view of an identification tag for a bag; FIG. 2 is a front view of the identification tag for a bag; FIG. 3 is a left side of the identification tag for a bag; FIG. 4 is a right side view of the identification tag for a bag; and,

FIG. 5 is a bottom view of the identification tag for a bag. The broken lines illustrate environment and form no part of the claimed design.
